LAUNDRY MACHINE

Arthur N. Beck, Jefferson County, Ky., assignor to General Electric Company, a corporation of New York

Application February 11, 1957, Serial No. 44,821

Term of patent 14 years

(Cl. D49—1)

Fig. 1 is a perspective view of a laundry machine embodying my new design, the opposite side thereof being the same in appearance as the side shown and the back being substantially plain; and

Fig. 2 is a view along line 2—2 in Fig. 1.

The dominant features of the design reside in the portions shown in full lines.

I claim:

The ornamental design for a laundry machine, substantially as shown and described.
